UNITED STATES PATENT OFFICE.

ADAMS HARE, OF ALLEGHENY, PENNSYLVANIA.

CAR-FENDER.

SPECIFICATION forming part of Letters Patent No. 536,518, dated March 26, 1895.

Application filed August 17, 1894. Serial No. 520,610. (No model.)

To all whom it may concern:

Be it known that I, ADAMS HARE, of Allegheny, county of Allegheny, State of Pennsylvania, have invented certain new and useful 5 Improvements in Car-Fenders, of which the following is a specification, reference being had to the accompanying drawings.

The object of my invention is to produce improvements in car fenders whereby the 10 guard may be carried ordinarily in a completely elevated and unobstructing position, but can be instantly let down in front of the car when an accident is threatened and by which the guard, under the weight of any- 15 thing that may be caught by it, will yield sufficiently to hold the same safely and securely.

In the accompanying drawings, Figure I is a side elevation of my fender elevated. Fig. II is a similar view of it depressed. Fig. III 20 shows the manner in which the guard yields under a weight to more securely sustain an object which it has picked up.

Referring to the figures on the drawings, 1 indicates a section of car body and 2 the front 25 dash thereof which should be securely fixed to the car body, and of sufficient strength to support the guard 3 and anything which it may pick up. The guard may be made of metal and may consist of a U-shaped outer 30 frame piece 4, a cross piece 5, and spacing bars 6 united into a firm, compact and strong frame, according to any approved method of construction. The ends of the frame piece 4 are provided with a hinge piece 7, and is de- 35 signed to be pivotally secured, as by pintles 8, to semielliptic springs 9, secured, as by bolts 10, to the bottom of the car body. Eye pieces 11 on the ends of the springs 9 receive the pintles for hinging the guard to the springs.

40 13 indicates a lever pivoted, for example, to an eye bolt 14 that passes through the dash near its base and is secured by a nut 15 on the inner side thereof. To the lever 13 suitable trip sustaining mechanism may be attached. 45 It may consist simply of a notched bar 16 pivoted, as indicated at 17, to the free end of the lever 13 and working in a guide frame 18 se- 50 cured, for example, to the top of the dash. The end of the arm 16 is provided with a ring or handle, by which the arm may be operated and which acts to limit the outward movement of the arm through the guide frame.

19 indicates a plate against which the notches of the arm 16 may catch for the adjustment of the arm.

55 20 indicates chains secured at opposite ends to the outer extremity of the guards, as indicated at 21, and at their opposite ends to the lever 13, as indicated at 22.

23 indicates supporting chains that are se- 60 cured, as indicated at 25, to the inner edges of the guard near its hinges, and at their op- 65 posite ends to the front of the dash, as indi- cated at 26. The chains 20 serve to support the guard upon its hinges and limit its move- 70 ment thereon, and to render the movement of the guard subservient to the lever 13. The chains 23 serve to limit the depressibility of the springs 9 and to afford an additional and rigid support for the inner end of the guard, 75 when the limit of the movement of the spring has been reached.

In practice, the arm 16 is, by the aid of its notches on its inner side, adjusted upon the plate 19 so that the guard is held at the re- 75 quired elevation above the track upon which the car moves.

In the case of a threatened accident it is usually impossible to apply the brakes quickly enough to prevent an injury to a victim, but 80 by the use of my guard provision may be made for picking up an object which is in front of the car and gaining time to apply the brakes and stop the car.

It is on many accounts desirable that the 85 guard should not be at all times within an operative distance from the track, and es- 90 pecially because of the danger to which it is ex- posed of meeting an obstruction and sustain- ing an injury to its mechanism. For that rea- 95 son I design to carry the guard ordinarily by the aid of the arm 16 in the elevated position, as shown in Fig. I. If an accident is threat- ened the motorman can lift the smooth upper edge of the lever 16 against the top of the 95 guard frame 18 and allow it to slide quickly through the guide frame, thereby instantly lowering the guard into position to perform its office.

The guard is normally sustained by the 100 springs 9 in a somewhat slanting position, as shown in Fig. II, but as soon as it receives the weight of a person, for example, it is depressed into the almost horizontal position shown in

Fig. III and holds the person securely as in a basket, thereby preventing its dislodgement and accidental injury after being picked up.

I do not confine myself to the details of construction herein shown and described, but reserve the right to modify and vary them within the scope of my invention.

What I claim is—

1. The combination with a car, of springs secured thereto, a guard hinged to the springs, means for elevating and depressing the outer end of the guard and limiting mechanism adapted to limit the expansion of the springs, substantially as specified.
- 15 2. The combination with a car, of a guard hinged thereto, a lever pivoted to said car and supporting the guard in an elevated position, a notched arm pivoted to the lever, a plate for fixing the adjustment of the notched arm and 20 a guide frame within which the notched arm works when it is being tripped, substantially as specified.

3. The combination with a car, of semi-elliptical springs secured thereto, a guard hinged to the springs, a lever adapted to sustain, the 25 guard, mechanism for adjustably sustaining the lever, and limiting mechanism secured to the guard and to the car for limiting the expansion of the springs, substantially as specified.

4. The combination with a car of springs secured thereto, a guard hinged to the springs, a lever pivoted upon said car, chains connecting the free end of the guard and the lever, and chains secured at their opposite ends to 35 the car and guard to limit the expansion of the springs or to sustain the guard in the event of accident, substantially as specified.

In testimony of all which I have hereunto subscribed my name.

ADAMS HARE.
